UNITED STATES PATENT OFFICE

ALBERT R. HAAG, OF PEORIA, ILLINOIS

WASHING MACHINE

Application filed January 31, 1931. Serial No. 512,535.

This invention has to do with improvements in washing machines, being directed more particularly to machines for cleansing wearing apparel though applicable to the treatment of all types of work involving fabrics.

The main object of the invention lies in producing a washing apparatus of a simple but exceedingly effective type wherein the work to be treated is kept in constant motion and by which the portions of the work, or the several articles comprised in the treated whole, are kept separated from each other by which a quick and thorough cleansing is made possible.

Another object is to furnish a novel form of mechanism in a washing machine to which reciprocations are imparted and from which water streams are forced upon and through the materials under treatment.

Still another object lies in imparting a reciprocating action to a cavitated body while immersed in the cleaning fluid, so ordered and arranged as to force or pump strong jets or streams of the fluid through the work under treatment and by which the separate articles of the work will be kept in constant movement and thoroughly separated and thus more quickly cleaned.

Further, an object is to provide in a washing mechanism an immersed reciprocating cavitated body that will act to force water through the work for cleaning the same rather than to operate upon the work mechanically.

Again, an object lies in constructing a cavitated body to operate in a submerged position, so appointed that in the reciprocations imparted to it the churning fluid will be forced in streams or jets under pressure upon the work at various angles whereby to accomplish quick cleansing due to the extreme turbulence of such fluid.

In addition to these objects invention is believed to lie in the novel arrangement of parts entering into the construction of the mechanism illustrated in the appended drawings forming part hereof though it is to be understood that minor changes may be made therein without departing from the aim of

the invention, and as lying within the appended claims.

Figure 1 is a vertical sectional elevation of a washing machine which includes the present invention.

55

Figure 2 is an elevation in part section of a portion of the invention shown in Figure 1.

Figure 3 is a horizontal section of the machine produced in line 3—3 of Figure 1.

Figure 4 is an enlarged detail of a portion 60 of what is shown in Figure 2, being an elevation.

Figures 5 and 6 are modifications of a wall structure, and

Figure 7 is a vertical section of part of a 65 wall structure shown in Figure 3 taken on line 7—7 of that figure.

The receptacle or tub for containing the work to be treated is represented at 1, and this may be mounted upon any suitable support or stand 2 which may include a shelf 2' constituting a rest for driving mechanism to be described later.

Erected in a central position upon the bottom 1' of the receptacle or tub 1 is a stem 3 75 provided with a bore 4. Said stem may include a base 5 by which to secure it to the said bottom in any suitable manner, the said bore 4 registering with an opening 6 in said bottom. A member taking the form of a cylindrical shell, in this instance, is identified by 5' and is erected in the tub and secured in place beneath the base 5, for example, the whole arrangement being arranged that leakage of water from the tub is prevented.

85

Within the bore 4 of the said stem 3 is a rod 7 having a length to extend above the latter and down through the bottom 1', the lower end of the rod having one end of a pitman 8 connected thereto. The other end 90 of the pitman has connection with the wristpin 9 of a crank-plate 10, for example, mounted on and rotated from the shaft 11 of a gear 11' housed in a gear-box 12, for example, a suitable power motor designated at 13 95 being belted to and adapted for operating the whole, it being understood, however, that any other form of power arrangement may be used the whole purpose of which is to impart reciprocations to said rod 7.

100

Affixed in any good manner to the end of the rod above the stem 3 is the upper end of a body or shell adapted to have reciprocations in a vertical direction with said rod. 5 This body or shell in the present instance comprises a cylindrical wall 14 greater in diameter than the shell or cylinder 5', there being a hood portion 15 mounted on the top of said wall in substantially a water tight manner 10 from which arises a portion 16 secured to the stem 7 in any desired manner together with a deflector portion or baffle 17, the latter being provided by preference only, and may not be used. The only purpose of said baffle 15 is that of preventing loss of water from the tub during the operation of the machine.

Below the lower edge of the wall 14 and affixed to it is a portion 18 closed around a cylindrical portion or thimble 19 and affixed 20 thereto, said thimble adapted to work in a snug sliding fit upon the mentioned shell or cylinder 5', it being noted that the thimble has one or more holes 20 therein above the member 18 or within the cavity of the described structure, said holes being used for drainage purposes only, and that there is a series of holes 21 in said cylinder conveniently located.

The cylindrical wall 14 is provided in this 30 instance with one or more series of holes 22, 23 which encircle said wall as best shown in Figure 3, see also Figure 2. As will be pointed out in the description of the operation, water streams are to be projected from 35 the holes 22, 23, and these said streams are to be directed preferably in a tangential direction, that is to say in a direction substantially tangential to said wall 14. It is to be here stated, however, that while said wall 14 40 may be cylindrical as described and shown it may, perhaps, be otherwise formed. The body may preferably be of larger diameter than the shell 5' in order that its wall 18 will impart added turbulence to the washing solution and the work as an assistance in the 45 cleansing action. In Figures 2, 3, 4 and 7, as will be seen, there is built out from the wall 14, at intervals, certain excrescences 14' through which said holes, or more properly 50 passages 22, 23 extend in directions tangential to said wall, all of said passages of both rows being directed in the same general direction. Again, as shown particularly in Figure 7 the upper series 22 while directed 55 in the manner described may also be directed upwardly, while the series 23 may be directed downwardly. While the described passages may be created as shown and described there are other ways of providing them in the wall 60 14. For instance, in Figure 5 the wall in a modified form may be perforated as at 142 and the metal at each of two sides may be distorted to provide a passage disposed at an angle to the surface from which the streams 65 are projected. In Figure 6, as another form,

the wall may be formed with angular portions 14⁴ in which the perforations 14⁵ may be created with the same end in view. These different methods are described as showing that it is not the intention to be confined to any one manner of accomplishing the desired result. It may be here stated, also, that but one of the rows of passages may be used and their axes may be directed somewhat after the manner shown in Figures 4 and 7.

In the figures it will be observed that the upper and lower enclosure portions 15, 18 at their perimeters preferably project beyond the wall 14 in addition to which a flange 14⁶ may lie between them. The two series 80 of holes thus lie between these extensions.

Upon setting the mechanism in action through the motor 13 the rod 7 will reciprocate carrying with it the body 14, 15, 18 the two extreme positions of the latter being shown in both broken and unbroken lines in Figure 1, said body being entirely submerged in the washing solution throughout its movements and consequently filled with such solution. In its upward stroke the solution is drawn into the body through the passages 22, 23 and the holes 21 of the cylinder 5', while in the downward movement the tendency to compress the solution results in pressure being created thereon by decreasing the cubic space in said body causing the solution to issue in strong streams or jets from said passages. Due to the inclination of the latter the solution will be given a rotary direction of movement around the tub. And since, also, the passages are inclined from the horizontal great turbulence of the solution results aided, of course, by the violent action set up by the body itself in its vertical movements, the treated work receiving the water jets into and through it, the extreme turbulence preventing the articles composing the work from becoming entangled and therefore exposed to through continuous cleansing action. The described flanges on 100 the wall 14 serve to prevent the clothes being drawn against the openings of the passages 22, 23 at the time the solution is drawn into the body, it being understood, however, that other means may be used that will serve a like 105 purpose.

The number of passages 22, 23, or at least their total effective area and the area of the holes 21 of the cylinder 5' may be so proportioned that the solution while being drawn into the body and expelled during the action of the mechanism may also move into and out of said holes 21, such movement through the latter assisting in the desired turbulence, and means may be provided for preventing the work being drawn into said holes.

Since the diameter of the body or agitator 14, 15, 18 is much less than that of the receptacle 1 a wide annular space is provided 130

between said body and the walls of the said receptacle for the free action therein of the solution and the work.

What is claimed is:

5. 1. A washing machine including in its construction mechanism comprising a receptacle, an open top shell erected therein, a cavitated body having a part engaging the shell in a snug sliding fit, the side walls of 10 the body being spaced from the walls of the receptacle and adapted for reciprocating movement with respect to the shell while submerged in a cleansing solution, said side walls of the body having perforations in submerged 15 positions directed toward the walls of the receptacle but being otherwise imperforate, its cavity closing said shell.

2. The invention according to claim 1 including perforations in the shell near its 20 lower extremity.

3. A washing machine including in its construction mechanism comprising a receptacle, an open top shell erected therein, a cavitated body having a part slidably engaging the shell, the side walls of the body being spaced from the walls of the receptacle and adapted for reciprocating movement with respect to the shell while submerged in a cleansing solution, said side walls of the body 25 having perforations directed toward the walls of the receptacle at an acute angle whereby water streams issuing from the same will cause the solution to take up a rotary movement around said body, the latter being otherwise imperforate, the cavity of the body closing the said shell and opening into it.

4. The invention according to claim 3 and wherein there are perforations in the shell 40 at its lower extremity.

5. Mechanism in a washing machine, including in combination with the receptacle of such machine an open top shell erected in said receptacle, a cavitated body having a 45 part slidably engaging said shell adapted for reciprocating movement with respect to it while immersed in a washing solution, said body having a greater diameter than the shell, its walls being widely spaced from the 50 walls of the receptacle and having perforations therearound directed toward the side walls of the latter and also directed at an acute angle whereby water streams issuing from such perforations will cause the solution 55 to take up a rotary movement around said body, said body being otherwise imperforate, its cavity closing the shell and opening into it.

6. In mechanism for a washing machine, a 60 hollow body for submergence in a cleansing solution and having in its sides a series of perforations directed at an acute angle therefrom whereby water streams issuing therefrom will cause the solution to take up a 65 rotary movement around such body, said

body having an opening in another of its walls, a member closing the opening, and means connected to one of the named parts for reciprocating it with respect to the other.

7. In mechanism for a washing machine, a 70 hollow body for submergence in a cleansing solution and having in its sides a series of perforations directed at an acute angle therefrom whereby water streams issuing therefrom will cause the solution to take up a rotary movement around said body, said body having an opening in another of its walls, a member to close the opening, and means connected with one of the named parts for reciprocating it with respect to the other by 75 which to create alternate suction and pressure in said body, the axes of certain of the named perforations in addition to their acute angular positions being inclined in the direction of movement of the reciprocating part.

8. In mechanism for washing machines, a 80 hollow body for submergence in a cleansing solution, the same having in a wall thereof orifices the axes of which lie at various angles to the surface thereof and having an opening, a member cooperating with the body extending into said opening to alternately create pressure and suction in both said body and member, and means to impart alternate 85 directions of movement to one of the described parts.

9. Mechanism for application to a washing machine including a hollow body for submergence in a cleansing solution, the same having an opening at one side, a member extending into the opening of the body cooperating with the latter for creating therewith alternate pressure and suction within said body, means to reciprocate one of the named parts with respect to the other, said body having perforations arranged around the same for egress and ingress of solution, the axes of said perforations being directed at an angle whereby water streams issuing therefrom rotate the solution in a path around the body, and means extending from the body adjacent the perforations for preventing materials under treatment from obstructing such perforations.

10. Mechanism for application to a washing machine including a hollow body for submergence in a cleansing solution, the same having an opening in one side, a member extending into the opening of the body cooperating with the latter for creating therewith alternate pressure and suction within said body, means to reciprocate one of the named parts with respect to the other, said body having perforations arranged around the same for egress and ingress of solution, the axes of certain of said perforations being directed at an angle whereby water streams issuing therefrom rotate the solution in a path around the body, and means extending 110

from the body adjacent the perforations for preventing materials under treatment from obstructing such perforations, and the axes of certain others of the perforations being 5 inclined at various other angles to cause turbulence throughout the entire bulk of the solution.

11. In combination with a receptacle for containing a cleansing solution and the work 10 to be treated, a submerged reciprocably mounted shell spaced from the side walls of the receptacle, there being perforations in the shell opening in the direction of the said side walls and in a direction substantially 15 tangential to the surface from which they open, said shell also having a relatively large opening in one wall thereof, and a member snugly closing the opening in a sliding fit whereby in the reciprocations of said shell 20 with respect to the member the solution will be drawn into and ejected from said perforations.

12. The combination including a receptacle for a cleansing solution and the work to be 25 treated, of mechanism including a hollow body erected in said receptacle, spaced from its walls and vertically reciprocable, means to reciprocate the same, said body having side walls provided with a series of perforations 30 opening therethrough, the axis of each of which is directed toward the side walls of the receptacle and inclined each at an angle to a radial line drawn from substantially the axial center of the receptacle, all of said passages 35 being directed in the same general direction, said body also having spaced upper and lower walls, one of said walls having an opening, and a cupped member snugly fitting in the opening, its open end facing the interior of 40 the body, the latter except as to the perforations being otherwise closed, and reciprocable with respect to said cupped member.

In testimony whereof I affix my signature.
